UNITED STATES PATENT OFFICE

92,464

DESIGN FOR A KNITTED SWEATER

Harry Goldman, Jamaica, N. Y.

Application March 23, 1934, Serial No. 51,163

Term of patent 3½ years

To all whom it may concern:

Be it known that I, HARRY GOLDMAN, a citizen of the United States and resident of Jamaica, Long Island, in the county of Queens and State of New York, have invented a new, original, and ornamental Design for a Knitted Sweater, of which the following is a specification, reference being had to the accompanying drawing forming part thereof.

The sweater is shown in bands of contrasting colors. It is understood that the colors may be others than those shown.

I claim:

The ornamental design for a knitted sweater, as shown and described.

HARRY GOLDMAN.
